J. SHIERY,
FIRE EXTINGUISHING MEANS FOR BOILERS.
APPLICATION FILED OCT. 29, 1914.

1,150,637.

Patented Aug. 17, 1915.

UNITED STATES PATENT OFFICE.

JOHN SHIERY, OF BRIDGEPORT, ILLINOIS.

FIRE-EXTINGUISHING MEANS FOR BOILERS.

1,150,637.

Specification of Letters Patent.

Patented Aug. 17, 1915.

Application filed October 29, 1914. Serial No. 869,342.

To all whom it may concern:

Be it known that I, JOHN SHIERY, residing at Bridgeport, in the county of Lawrence and State of Illinois, have invented 5 a new and Improved Fire-Extinguishing Means for Boilers, of which the following is a specification.

This invention has reference to that class of devices or means attachable to steam boilers and adapted for extinguishing the boiler fire before the water within the boiler reaches a low or danger point, and my said invention has for its object to provide a means of the character stated of a compact and economical construction, in which the several parts are so designed that they may be readily applied to the various construction of boilers and which effectively serve their intended purpose.

With other objects in view, my invention embodies the peculiar arrangement and combination of parts, all of which will be herein-after fully explained, specifically pointed out in the appended claims, and illustrated 25 in the accompanying drawing, in which:

Figure 1 is an end elevation of a boiler with my invention operatively combined therewith. Fig. 2 is a vertical section taken on the line 2—2 on Fig. 1, the controlling 30 valve being shown at the closed or normal position. Fig. 3 is a detail vertical section showing the parts at the elevated or open position.

My improved attachments, which act as 35 a safety device for boilers, consists primarily of a tapering casing 1, the upper or contracted end of which terminates in an opening 2, that is internally threaded to receive the lower threaded end of an expansion pipe section or tube 3, the upper end 40 of which threads into a cap piece 4 provided with a transverse or crown seat 40, the purpose of which will presently appear.

The lower end of the casing 1 is open and 45 is internally threaded, as at 20, to receive the threaded flange 50 of a removable bottom section 5, which includes a hollow pendent casing-like portion 51 that has a threaded outlet 52 to receive the upper end 50 of an outflow pipe 6, that joins with the fuel feed pipe 7 that conveys the gaseous fuel into the boiler at a suitable point below the door, as is indicated on Fig. 1, by reference to which it will be also seen the 55 fuel pipe has the usual cutoff valve 71 located beyond the outflow pipe connection

61. The bottom section 51 has a central outlet 53 that also forms a valve seat for the controlling or ball valve 8 and it also has a central pendent guide aperture 54 in which 60 is slidably held a lifting rod or stem 9, the upper end of which terminates in a head 90, which, under normal conditions, is positioned a slight distance below the valve 8, when the latter is at the normal or closed 65 position, indicated in full lines on Fig. 2 of the drawing. The lower end of the lifting stem 9 rests upon an adjusting screw 10 that threads into a cross bar 11 supported on hanger rods 12^a that form a part of a yoke 70 12 pendently supported on the cap piece 4 and which engages the seat 40 thereof, as shown. Casing 1 has an inlet 15 that receives one end of a pipe connection 16, the other end of which, as shown, joins with the 75 lowermost one of the water gages 16 on the boiler. 18 designates a control valve in the pipe connection 16. The cap member 4 has a lateral extension 41 that carries a pet cock 42, (see Fig. 1).

43 is a packing gland for the lift rod that co-operates with the controlling or ball valve.

From the foregoing description taken in connection with the accompanying drawing, 85 the operation and advantages of my invention will be readily understood.

As the water in the boiler lowers to a point below the lower gage level, steam enters the casing and passes up into the pipe 90 section or tube 3, the latter, by reason of its expansion, lengthens and in doing so it lifts the yoke member with the cross bar and thereby elevates the lift rod sufficiently to cause it to engage and raise the valve 8 95 from its seat and thereby allows the water in the casing 1 and the steam back of it to pass through the outflow pipe into the fuel pipe and thus extinguish the fire therein.

In practice, the pet cock 42 may be occasionally opened to clear the expansion pipe or tube of dirt and scale and for relieving the pressure of steam when the valve in the pipe connection is closed, following the fire extinguishing operation, and thus permit 100 the said expansion pipe or tube to quickly contract in order to allow valve 1 to drop back to its closed position to bring the parts ready for another operation.

My invention is particularly adapted for 110 use on boilers in the oil field work or at any place where gaseous fuel is used.

What I claim is:

1. In a safety device for boilers, the combination with the fuel supply pipe and the boiler; of a casing having an inlet and an outlet, a pipe connection that joins the inlet with the boiler, an outflow pipe that joins the outlet with the fuel pipe, a valve within the casing that normally seats over and closes the casing outlet, an expansion tube 5 that connects with the casing, a valve shifting element, and a connection between the said shifting element and the expansion tube for moving the shifting element to move the valve from the casing outlet as the said tube 10 expands.
2. In a safety device for boilers, the combination with the fuel supply pipe and the boiler; of a casing having an inlet and an outlet, a pipe connection that joins the inlet 15 with the boiler, an outflow pipe that joins the outlet with the fuel pipe, a valve within the casing that normally seats over and closes the casing outlet, an expansion tube that connects with the casing a valve shifting element, a connection between the said shifting element and the expansion tube for moving the shifting element to move the valve from the casing outlet as the said tube 20 expands, a pet cock connected with the said tube for clearing it and a control valve in 25 the pipe connection from the boiler to the casing.
3. In a safety device for boilers, the combination with the fuel supply pipe and the 30 boiler; of a casing having an inlet at the upper end and an outlet in the bottom thereof, a pipe connection that joins the inlet with the boiler, an outflow pipe that connects the outlet of the casing with the fuel 35 pipe, a ball valve within the casing that normally closes the outlet thereof, an expansion tube connected to and extending upwardly from the casing, a cap piece on the upper end of the tube, a yoke pendently supported from the said cap piece, a cross bar hung on the said yoke, and a lift rod sup- 40 ported by the bar and adapted to engage and lift the aforesaid valve as the yoke and the bar rise under the expansion of the tube.
4. In a safety device for boilers, the combination with the fuel supply pipe and the 45 boiler; of a casing having an inlet at the upper end and an outlet in the bottom thereof, a pipe connection that joins the inlet with the boiler, an outflow pipe that connects the outlet of the casing with the fuel pipe, a ball valve within the casing that normally closes the outlet thereof, an expansion tube connected to and extending upwardly from the casing, a cap piece on the upper end of the tube, a yoke pendently supported from the said cap piece, a cross bar hung on the said yoke, and a lift rod mounted on the said adjustable support 50 and adapted to engage and lift the aforesaid valve as the yoke and the bar rise under the expansion of the tube.

5. In a safety device for boilers, a casing open at its upper and lower ends, a plug screwed into the lower end of said casing, said plug having a passage provided with a web, said web having a valve seat, a ball valve adapted to engage said seat, a packed pin adapted to engage said ball valve and projecting to the outside of said plug, an expansion tube screwed into the upper opening of said casing, a member having a saddle portion on the upper end of said expansion tube, a yoke fitted over said saddle portion, 55 a cross bar carried by said yoke, and extending beneath said pin and an adjusting screw carried by said cross bar to engage with said pin, said casing having an opening adapted to be connected with the water 60 space of a boiler and said plug having a discharge outlet, substantially as shown and for the purposes described.

JOHN SHIERY.
